UNITED STATES PATENT OFFICE.

PERCY M. ELLIOTT, OF CHICAGO, ILLINOIS; NELLIE S. ELLIOTT, EXECUTRIX OF SAID
PERCY M. ELLIOTT, DECEASED, ASSIGNOR TO CAMEL COMPANY, OF CHICAGO,
ILLINOIS, A CORPORATION OF ILLINOIS.

FLUSH-CLOSING SLIDING DOOR.

Application filed January 6, 1923. Serial No. 610,964.

This invention relates to sliding doors of the type in which the door, upon reaching closing position, is displaced bodily in a direction transverse to the plane of sliding in order to cause it to enter between the members of the car body which define the door opening and thereby produce a so-called flush closure.

The object of the invention is to provide improved means for suspending the door with freedom to execute its movement into and out of the door opening, as well as means for imparting its said movements; and the invention consists both broadly and specifically in the means hereinafter described and particularly pointed out in the claims.

In flush closing sliding doors it is customary to introduce the forward edge of the door to its ultimate position within the confines of the door opening by diverting or inclining the forward portion of the track upon which the door travels, and equipping the rear portion of the door with means which enables it to move bodily, transversely to the direction of sliding, into and out of its tightly closed position, and the preferred embodiment of the present invention follows this plan of manipulation, although, as will be seen, the invention which resides primarily in the means for suspending the door with freedom of the aforesaid transverse movement as well as the means for imparting such movement, or in a door equipped with such means, might be applied to both ends of the door if conditions made it desirable to do so.

In carrying out the invention, the door is suspended through means of a hanger or hangers adapted to travel upon a track to bring the door to and from its position in front of the opening which it is to close, and this hanger is constructed not only with means for attaching it to the door to be suspended, but with means which permits it to change its angular relation to the door in the direction transverse to its travel upon the track, so that while the hanger is fixed against displacement on the track in such direction, the door is rendered pendulous in said direction; and means are provided, preferably upon the door, for imparting such pendulous movement; the pendulous connection being preferably developed

through means of a hinge interposed between the hanger and the plate through which it is attached to the door; the means for imparting the pendulous movement consisting preferably of a rock shaft carrying at its end an eccentric or crank acting upon a member fixed with relation to the car body, and preferably a portion of the track upon which the car runs and preferably through means of a follower which remains in embracing relation to the track at all times and with which the crank arm engages; the door being provided with a curb bar or other suitable portion which limits its outward movement, as, for instance, by projecting vertically behind the hanger, which in turn is kept from outward displacement by engagement with the track member; and the track and hanger being disposed to support the door normally in its sliding position so that in swinging off of its center to flush position, the door will be slightly raised and will therefore tend to gravitate out of its flush position to a position when released and subjected to a minimum unseating force.

In the accompanying drawings, in which the preferred embodiment of the invention is shown by way of illustration—

Figure 1 is a side elevation of a portion of a freight car and its sliding door to which the several features of the present invention are applied.

Figure 2 is a vertical section on the line 2^x—2^x of Figure 1, drawn on an enlarged scale and with the intermediate portion of the door omitted, and the parts being in positions assumed when the door is ready for sliding.

Figure 3 is a section on the line 3^x—3^x of Figure 1, showing on an enlarged scale the means for moving the door into and out of tightly closed or flush position.

Figure 4 is a top plan view of the track; and

Figure 5 is a horizontal section on the line 5^x—5^x of Figure 1.

1 represents a car body having a track 2, and 3 and 4 represent hangers supported on said track with freedom of travel longitudinally thereof, and 5 represents a door supported by said hangers. As shown in Figure 4, the track 2 is spaced outwardly from the body 1 of the car for the greater part of

the length of the track, but inclined inwardly at its forward end 1^a, with the result that when the door 5 travels to position in front of the opening which it is to close, the forward end of the door will be retired within the outer plane of the door frame, while the rear portion of the door hangs pendulously away from the car body but in position to be moved bodily inward in a direction transverse to its sliding movement in order to bring the remainder of the door flush with the door frame, or to a firm seating therein. In order that the door may execute this movement transversely to the length of the track, hanger 4, as will be best seen in Figure 2, is connected by means of a hinge pintle 6 with the plate 7 by which the hanger is secured to the door 5; said pintle extending parallel to the track 2 so that the resultant hinging action is transverse to the track; and a roller 8, through which the hanger 4 bears upon the track 2, has a convex tread which facilitates rocking movement of the hanger on the track. The hanger is thus adapted to change its angular relation to the door in a direction transverse to that in which the door slides, and the door can consequently move into and out of the door opening after the manner of so-called flush closing sliding doors.

Important features of the present invention consist in constructing the track 2 with a horizontally presented tread portion 2^a and a vertical guard 14 depending therefrom, and having the hanger 4 equipped with a roller 8^a engaging beneath the tread portion 2^a without restricting the rocking movement of the hanger, and with the curb 5^a that engages behind the guard 14 for limiting the outward pendulous movement of the door; also the employment of the curb 5^a for seating the door against the outer face of the wall which defines the doorway, in addition to limiting the outward pendulous movement of the door by engaging the guard 14.

But as will be seen from Figure 2, the track 2 and the position of the hanger 4 upon it are such that when the door 5 is permitted to assume normal position of suspension it will hang away from the body of the car and out of the recess of the door opening, so that it is free to slide to open position. Moreover, in entering the recess of the door opening, the arc through which the pintle 6 swings has a slight upward moment in the inward movement of the door, and therefore a slight gravitation in the outward movement, and this correspondingly assists in the releasing of the door from its flush position in the doorway.

In order to impart inward movement to the door, and preferably outward movement as well, the rock shaft 9 is mounted in bearings 10 on the door, and carries at its upper

end a crank arm 11 whose pin 12 enters an eccentric follower 13 having a horn 13^a and engaging the inner as well as the outer face of a guard flange 14 depending from the track 2. By rotating shaft 9 through an angle of, say, 90° the door will be caused to move from the position shown in Figure 2 to the position shown in Figure 3. Rotation can be imparted to the shaft 9 through any suitable means, such, for instance, as the controlling lever 15 shown in Figure 1; and this controlling lever may be secured after the manner of a hasp through means of hasp lock 16, and thus serve as a locking means as well as a means of control.

In order to secure the bottom of the door in flush or tightly closed position, a bottom guide 17 is rendered adjustable by equipping it with a two-armed guide wall 18 pivoted thereon at 19 and so constructed that when rotated by its lever 20 to the position of Figure 3, the bottom curb 21 of the door will be held by the arm 18^a in closed position, whereas a rotation of the arm 20 through an angle of, say, 90° to the right from the position of Figures 1 and 3 will bring the arm 18^b of the adjustable bottom guide opposite the door curb 21, and this end 18^b, being in a plane more remote from the face of the car than the end 18^a, will permit the door to hang away from the recess of the door opening. The controlling arm 20 of the adjustable bottom guide 17 may be secured by a seal or other means passing through its fin 20^a and through a keeper 22, as shown in Figure 3.

In illustrating the present invention the details of car construction selected are those of a double sheathed car, but it is to be understood that the invention is applicable to flush car doors for other constructions of cars, for instance, single sheathed and all metal cars, and for other structures as well.

I claim:

1. A railway car having a side wall providing a doorway, a door adapted to fit within said doorway and having a curb projecting over and seating against the outer face of said wall at the edges of said doorway, a track, a hanger supported by said track for carrying said door with freedom to move pendulously in a direction transverse to the plane of said door, said track being provided with a depending guard overlapping said curb and adapted to engage said curb to limit the outward pendulous movement of said door.

2. A railway car having a side wall providing a doorway, a door adapted to fit within said doorway and having a curb projecting over and seating against the outer face of said wall at the edges of said doorway, a track, a hanger supported by said track for carrying said door with freedom to move pendulously in a direction

- transverse to the plane of said door, said track being provided with a depending guard overlapping said curb and adapted to engage said curb to limit the outward pendulous movement of said door, and rotary means carried by said door adapted to move said door pendulously to a position flush with said car wall.
3. A railway car having a side wall providing a doorway, a door adapted to fit within said doorway and having a curb projecting over and seating against the outer face of said wall at the edges of said doorway, a track, a hanger supported by said track for carrying said door with freedom to move pendulously in a direction transverse to the plane of said door, said track being provided with a depending guard overlapping said curb and adapted to engage said curb to limit the outward pendulous movement of said door, and rotary means carried by said door adapted to move said door pendulously to a position flush with said car wall, said track having a portion of its length inclined toward said car wall whereby to direct a side edge of said door toward closing position.
4. A railway car having a side wall providing a doorway, a door adapted to fit within said doorway and having a curb projecting over and seating against the outer face of said wall at the edges of said doorway, a track, a hanger supported by said track for carrying said door with freedom to move pendulously in a direction transverse to the plane of said door, said track being provided with a depending guard overlapping said curb and adapted to engage said curb to limit the outward pendulous movement of said door, and rotary means for moving said door transversely.
5. A railway car having a side wall providing a doorway, a door adapted to fit within said doorway and having a curb projecting over and seating against the outer face of said wall at the edges of said doorway, a track, a hanger supported by said track for carrying said door with freedom to move pendulously in a direction transverse to the plane of said door, said track being provided with a depending guard overlapping said curb and adapted to engage said curb to limit the outward pendulous movement of said door, and rotary means for moving said door transversely, said rotary means being provided with locking means for preventing rotation of said rotary means and for locking said door in closed position.
6. In a car, a car wall providing a doorway, a sliding flush closing door operatively associated therewith, a track having a depending guard flange, a hanger carried by said track having a roller through which it bears upon said track with freedom of rocking thereon and having a projection engaging the underside of said guard flange, means for pivotally attaching said hanger to said door, and rotary means for positively moving said door in a direction transverse to said car wall.

Signed at Chicago, Illinois, this 4th day of January, 1923.

PERCY M. ELLIOTT.
